CLAIM

The ornamental design for a ring wearable device, as shown and described.

DESCRIPTION

FIG. 1 is a top-front perspective view of the ring wearable device, showing our new design;

FIG. 2 is a bottom-rear perspective view of the design illustrated in FIG. 1;

FIG. 3 is a top view of the design illustrated in FIG. 1;

FIG. 4 is a bottom view of the design illustrated in FIG. 1;

FIG. 5 is a right side view of the design illustrated in FIG. 1, the left side view being a mirror image thereof;

FIG. 6 is a front view of the design illustrated in FIG. 1; and,

FIG. 7 is a rear view of the design illustrated in FIG. 1.

1 Claim, 6 Drawing Sheets
